UNITED STATES PATENT OFFICE.

JAMES B. FARQUHAR, OF VANCOUVER, BRITISH COLUMBIA, CANADA.

MUFFLE.

1,269,270.

Specification of Letters Patent. Patented June 11, 1918.

Application filed December 18, 1916. Serial No. 137,671.

To all whom it may concern:

Be it known that I, JAMES B. FARQUHAR, a citizen of the Dominion of Canada, residing at Vancouver, in the Province of British Columbia, Canada, have invented certain new and useful Improvements in Muffles, of which the following is a specification.

This invention relates to an improved construction in a muffle of that class used 10 by assayers but applicable to any muffle applied for any purpose.

These muffles are commonly formed with the floor, walls and arch integral and owing to irregular stress of expansion, they are 15 subject to fracture in the walls generally adjacent the junction of the floor thereto. It is to remove this cause of fracture that the subject matter of this application has been devised.

20 The invention is particularly described in the following specification, reference being made to the drawings by which it is accompanied, in which:

The figure is a perspective view of a muffle 25 constructed in accordance with my invention.

In these drawings 2 represents the floor, 3 the walls and roof of the muffle, 4 being the closed end which is apertured at 5 to 30 permit escape of the fumes given off from the material being treated within the muffle. Instead of, as is usual, forming the floor integral with the walls and roof, which integral construction is the cause of frequent 35 fracture, the floor 2 is formed as a separate piece onto which the lower edges of the walls 3 and back end 4 are seated.

To retain the walls in position on the floor 2 and prevent intrusion of the flue gases 40 within the muffle at the joint, the bottom is formed with a groove 6 to receive the lower edges of the walls and back, in which groove the thickness of the walls and back are an easy fit to permit expansion of one part in 45 relation to the other.

The outer edge of the groove 6 or inner edge of the raised bead 7, may be beveled and the space 8 so left is filled with a suitable refractory sealing material such as bone ash.

50 The heat being applied to the outer side of the muffle, the greater expansion of the outer side will tend to force the lower ends of the walls 3 inward, while the direct expansion of the bottom 2 will be outward.

55 By constructing the muffle in two parts as

described, this unequal expansion of one part in relation to another imposes no destructive stress in the side walls, and in consequence a greater life is insured for the muffle, while the provision of the groove 6 or lip 7 locates the upper part definitely in relation to the lower and prevents indraft at the joint which is rendered more effective by a sealing material applied to the joint.

I am aware that prior to my invention 65 muffle furnaces have been sectionally constructed to provide for the effect of unequal expansion under heat, and to avoid having parts of exceptional size or weight for transport. I am also aware that muffle furnaces 70 have been designed with an inner or muffle chamber sectionally constructed as a part of the furnace, but where this has been done the sectional construction has been a necessary requirement in attaining the desired 75 object of providing an inner or muffle chamber with a thicker roof to prevent accession of heat therethrough, and thereby obtain a more uniform distribution of heat within the inner chamber, and not to provide for 80 the opposite expansions of the floor, walls and roof of a muffle *per se*. In a muffle furnace where the outside is exposed to the atmosphere and the inner side to the extreme heat of a furnace the requirement of providing for the opposed expansions is obvious, but with a muffle, as a separate article of manufacture, the requirement is not so obvious as the entire muffle is inclosed within the furnace, but the same conditions of opposed 85 expansions prevail in a muffle as in a muffle furnace, though not to such an extreme degree, as the heat of the furnace which passes through the muffle walls is applied from the outside, so that the outer side 90 must be heated in excess of the inner side and opposed stresses are imposed which lead to frequent fracture.

Manufacturers of muffles have endeavored to meet the defect by rounding the corners 100 at the junctions of the floor and roof to the walls and by thickening the walls toward the floor junctions where the opposed expansions meet, but within my knowledge no attempt has been made to meet the defect 105 by sectional construction leaving each part free to expand with provision for locating one part on the other and for closing the joint.

Having now particularly described my in- 110

vention, I hereby declare that what I claim as new and desire to be protected in by Letters Patent, is:

A muffle constructed in two parts, one an 5 arched wall and roof member, and an integrally formed end wall, the other part comprising the floor member and being provided with an upwardly projecting edge bead to receive the bottom edge of the wall 10 of the first part, the inner edge of said bead being beveled outwardly to provide a space

at the outside of the wall, and a sealing material located in said space, said floor member also being recessed to receive the lower edge of the walls of the first part, said recess at the inner side having a vertical wall surface against which the side of the lower edge of the wall of said first part rests, all being arranged substantially as shown and for the purpose described. 15

In testimony whereof I affix my signature. 20
JAMES B. FARQUHAR.
